[57] CLAIM

The ornamental design for cutting blade for rotating cutters, as shown and described.

DESCRIPTION

FIG. 1 is a perspective view of a cutting blade for rotating cutters according to the design;

FIG. 2 is a plan view of the arcuate V-shaped edge of the blade;

FIG. 3 is an end view;

FIG. 4 is a side view;

FIG. 5 is an opposite end view;

FIG. 6 is a plan view of the edge of the blade opposite that shown in FIG. 2;

FIG. 7 is an opposite side view;

FIG. 8 is a perspective view of a second embodiment of the design shown in FIG. 1;

FIG. 9 is a plan view of the beveled edge of the blade;

FIG. 10 is an end view;

FIG. 11 is a side view;

FIG. 12 is an opposite end view;

FIG. 13 is a plan view of the edge of the blade opposite that shown in FIG. 9; and,

FIG. 14 is an opposite side view.
